UNITED STATES PATENT OFFICE

CLINTON L. BIGLER AND JOHN KLOOS, OF ALLIANCE, OHIO, ASSIGNORS TO THE MORGAN ENGINEERING COMPANY, OF ALLIANCE, OHIO

INGOT STRIPPER

Application filed January 5, 1929. Serial No. 330,583.

This invention relates to an improved apparatus for stripping a mold from a metal ingot, and the primary object of the invention is to provide an apparatus whereby the force employed to pull an ingot from a mold will be counteracted by means for imparting such force to the mold to facilitate the separation of the ingot from the latter.

It has heretofore been proposed to push an ingot from an open bottom mold while lifting the mold relatively to the ingot, but so far as we are aware, previously, it has never been proposed to lift the ingot from a closed bottom mold, while causing the lifting stress to be transmitted to the mold for forcing the latter downwardly while the ingot is being lifted.

Another object of the invention is to furnish a portable stripper crane adapted particularly for handling ingots out of closed bottom molds, in which the ingots are cast with the larger part uppermost. This type of mold is usually provided with a "hot top" made of some refractory material which is broken away from the ingot in the present invention, by the tong bits before the ingot is withdrawn from the mold.

Another object is to furnish such an apparatus including ingot handling tongs designed to lift or pull the ingot out of the mold while a double acting screw cooperating with the tongs is serving to position arms which hold the ingot mold down. The machine is designed to produce a very great pulling or stripping force with the tongs, say as high as 150 tons, and as the tongs are manipulated to pull the ingot from the mold, the lifting force is automatically imparted to the mold for preventing the latter from rising with the ingot.

A still further object is to provide a machine of this character, having novel ingot raising tongs with special means for manipulating the same.

A still further object is to furnish a stripping machine, including mold engaging arms, and novel means for moving the lower ends of the arms toward or away from each other.

With the foregoing objects outlined and

with other objects in view which will appear as the description proceeds, the invention consists in the novel features hereinafter described in detail, illustrated in the accompanying drawings, and more particularly pointed out in the appended claims.

Referring to the drawings,

Fig. 1 is an elevation of the improved apparatus.

Fig. 2 is a similar enlarged view, partly in vertical section, and with certain parts omitted to facilitate illustration.

Fig. 3 is an enlarged vertical sectional view of certain essential features of the mechanism.

Fig. 4 is a side elevation of the parts shown in Fig. 3.

Fig. 5 is an enlarged vertical sectional view of a detail.

Fig. 6 is an enlarged horizontal sectional view of a detail on line 6—6 of Fig. 2.

Referring first to Fig. 1 it will be noted that the mold 1 is of the closed bottom type, and has an internal chamber of substantially inverted cone shape, to facilitate the withdrawal of the ingot 2 upwardly. As is usual, such mold is provided with a hot top 3 that functions as an extension to be grasped by the tongs herein-after described, for removing the ingot.

Upper lugs 4 project from opposite sides of the mold, and are designed to be engaged by suitable lifting mechanism when the mold is to be shifted from place to place, and similar lugs 5 are arranged on the lower part of the mold, below the center of gravity of the latter, to be employed when the mold is to be lifted and turned upside down.

One or more of such molds may be arranged on a stool 5a, mounted on top of a car 6, which rolls along the rails 7.

These rails are arranged parallel to overhead rails 8, on which the stripping mechanism carriage travels. Such carriage preferably consists of end blocks 9 forming bearings for rollers 10 that travel on the tracks 8 and support spaced girders 11 which carry tracks 13 for the wheels 14 of a trolley 12.

From the foregoing, it will be apparent

that the girders 11 may be moved along the tracks 8, and that the trolley 12 may be shifted along the girders in lines perpendicular to the tracks 8.

5 The trolley supports suitable motors, clutches, gearing and winding drums, employed in manipulating the mechanism, and a depending extension (Fig. 2) of the trolley which is suspended from the carriage 14 and arranged between the girders 11, supports a cage 15 to be occupied by the operator, and which is adapted to contain the electrical control apparatus (not shown) for the operating mechanism of the trolley 12. The cage 15 provides a platform, so located that the operator can obtain a satisfactory view of the ingot while it is being stripped and removed from the mold.

20 A double screw 16, forming an important part of the operating mechanism, has an upper thread 18 which is pitched opposite from the lower thread 19. For example, it is preferred to provide the part 18 with a right hand thread, and the part 19 with a left hand thread, and these threads should be of the buttress type, with the straight side of the threads toward the middle of the screw, for the reason that when the pressure is on the screw, the screw is under tension, and the 25 forces act in the directions indicated by the arrows *a*—*b*.

25 The double screw has an upwardly projecting extension 21 which is of square cross section, (Fig. 6) and is adapted to slide up and down in a bushing 22, having a square bore. This bushing is provided on the stripper barrel 23, which extends through the trolley. Suitable gearing on the trolley is employed to rotate a gear 24, fast on the barrel 23, and when the gear 24 is rotated, similar 30 rotation is imparted to the screw. At the top of the barrel 23, a tubular cover 25 is provided, and this cover has a cap 26, and the cover and cap enclose the screw extension 21, and protect the latter and the screw from dust and dirt. Of course, the cover is of 35 sufficient length to provide for the upward movement of the screw extension 21.

40 The screw 18 is positioned within a structural steel shell or tube 27, which depends from, and is supported by the trolley frame 14, and acts as a guide for the stripper mechanism. Such mechanism can be raised and lowered in the shell by cables 28 and 29, (Fig. 45 3), which are wound at their upper ends on hoisting drums that are located on the trolley, and driven by electric motors through gear trains. These parts are shown more or less diagrammatically in Fig. 1, but as they 50 are of known construction, it will be unnecessary to describe the same in detail, except to say that the cables 28 are operated by one pair of drums acting in unison, and the cables 29 are operated by another pair of drums acting 55 in unison.

The weight of the suspended portion of the stripping mechanism is partially counter-weighted by counter-weights (not shown), which slide up and down in the shell 27, but in direction opposite to that of the direction 70 of the motion of the suspended portion of the stripper mechanism. Each counter-weight may be connected to a cable passing over a sheave on the trolley, and connected at its opposite end to the stripper housing 34, hereinafter referred to. 75

The upper screw 18 works in a non-rotary nut 31 which is secured at its upper end, as shown at 33, to the upper end of the housing 34, and the lower screw 19 engages a non-rotatable nut 32 which is fixed to the upper end 80 of the ram 35.

85 Stripper arms 36 are journaled on fulcrum pins 37, mounted on the housing 34, and the upper ends of these arms are pivotally connected at 38 to links 38a. These links are pivotally connected at their opposite ends to depending arms on rocking levers 40, which are pivotally mounted at 41 on the housing 34. Each of these levers has an outwardly extending arm connected at 42a to the lower end of one of the cables 28, and each lever also has an inwardly extending arm connected at 43a to one of the cables 29. From 90 this it may be seen that when the weight of the suspended portion of the stripper mechanism falls upon the inner cables 29, the levers 40 will force the upper ends of the stripper arms 36 inwardly, and in consequence, the lower ends of these arms will be moved outwardly, as will be clear from a consideration 95 of Fig. 3. On the other hand, when the weight of the stripper mechanism is transferred to the hoist cables 28, the reverse action occurs, and the arms are swung toward 100 the axis of the mold.

105 Each arm 36 is provided with a cross member or abutment 41a, curved horizontally and designed to rest on the upper edge of the mold, while the ingot is being stripped from the latter. The lower ends of the arms are provided with eyes 42, adapted to engage the lugs 4 or 5 on the mold, when the mold is to be lifted or handled by the machine.

110 As best shown in Figs. 4 and 5, the lower end of the ram 35 is fixed to the tongs cap or housing 43, provided internally with downwardly diverging guides or tracks 44 that receive trunnions or rollers 45 on the upper ends of tong levers 46. These levers are pivotally mounted on shafts 47 which are supported by a pair of links 48, and the shafts and links are held in assembled relation by keeper plates 49 that are secured to the links 115 and extend into slots cut in the peripheries 120 of the shafts.

125 Rods 50 support the links, and these rods have their lower ends connected to the links at the points 52, while their upper ends slide through openings 55 in a flange at the lower 130

end of the housing 34. Above the flange, each rod is provided with a nut 54, threaded on the upper end of the rod, and used for adjusting a buffer spring 53 which surrounds 5 the rod and is located between the nut and said flange.

Each of the tong levers 46 is provided at its lower end with a bit 56, preferably made of hardened steel, and fitted to the tong lever 10 in such a manner as to be readily replaced as the bit wears down. Each bit is held in place by a tapered wedge key 57, and the lower edge 58 of the bit forms a projection for the lower edge 59 of the tong lever. Each bit is 15 partially kept in place in its respective lever by a shoulder 60.

From the foregoing, and an examination of Fig. 5, it may be seen that when the cap 43 is raised by manipulation of the screw 16, 20 that the points of the bits will be caused to move in arcs which extend upwardly from the top of the mold, and consequently, as the bits move toward one another, they also rise so they will not alone grip the hot top of the 25 ingot, but they will simultaneously lift the ingot out of the mold. In order that this operation may be readily understood, note that the nut 32 of the ram 35 which carries the cap 43, is normally at the lower end of 30 the screw 19, and consequently, when the screw is turned in the proper direction, the nut, ram and cap 43 will be lifted. As the cap rises, the rollers 45 on the upper ends of the tongs will be forced away from one another by the diverging guides of the cap, and simultaneously, the bits 56 of the tongs will be moved inwardly and upwardly, so that the powerful force exerted by the screw 35 is imparted to the bits, and they first break 40 away refractory portions of the hot top, and after they have penetrated the ingot top sufficiently to give them a good hold on the ingot, the entire pulling or stripping power of the machine is brought into play, and the 45 ingot is pulled loose from the mold.

While this action is taking place, the upper screw 18 is tending to pull the screw 31 downwardly, so that this force is imparted to the housing 34, which, through the pins 37, imparts the same to the arms 36, and as the latter are now resting on the top of the mold, they tend to push the mold downwardly at the same time as the ingot is pulled upwardly.

55 In operating the mechanism, the operator in the cage 15, in case he desires to simply lift a mold and shift it from one place to another, works his controls in such manner as to bring the overhead trolley directly over the mold that is to be handled. The trolley is then halted, and by manipulating other controls, the operator lowers the suspended portion of the mechanism while the weight is borne by the cables 29. Obviously, this 65 causes the arms 36 to be spread apart while

the mechanism is lowered into position to grasp the mold. When the suspended part of the mechanism has been lowered sufficiently, the operator will shift the burden on to the cables 28, and this will cause the arms 36 70 to move toward one another in order that the eyes at the lower ends of the arms may engage the trunnions 4 of the mold. Now, if the cables 28 are wound on their drums, the extension 21 of the screw 16 will be raised 75 in its barrel 23, and at the same time, the mold may be lifted, and of course, when the mold has been raised sufficiently, the crane may be shifted to any desired point, and the mold may be deposited. In such operation, the winding drums of the cables 28 are rotated in proper direction to unwind these cables, so that the suspended part of the mechanism descends. When the mold reaches its new supporting surface, the weight is 80 again shifted on to the cables 29, and this will cause the arms 36 to move apart and release the mold.

Whenever it is desired to turn a mold upside down, the eyes 42 of the arms 36 are 90 brought into engagement with the trunnions 5, and then when the mold is lifted, it will reverse, due to the trunnions 5 being located below the center of gravity of the mold.

When an ingot is to be pulled from a mold, it will be noted that the burden of loosening the ingot in the mold is not placed upon the cables 28, 29, or especially upon the rods 50, but this burden is placed directly from the tongs on to the cap 43 which is moved upwardly by the screw 16, while the shafts 47 remain at the same horizontal elevation. The stress on the cap is imparted by the ram 35 to the nut 32, which rises on the screw 19 and thus places the strain on this screw. 100 However, as the part 18 of the screw is engaging the nut 31, and the latter cannot move downwardly, owing to the arms 36 resting on the top of the mold, it will be seen that the burden is transferred to the mold, but at 105 the same time, the screw 16 will rise in its barrel.

From the foregoing description, it is believed that the construction, operation and advantages of the invention may be readily 115 understood, and it is apparent that various changes may be made in the details disclosed without departing from the spirit of the invention, as expressed in the claims.

What we claim and desire to secure by Letters Patent is:

1. In an ingot stripper, means for applying downward pressure against an ingot mold, and stripping mechanism directly connected to said means to simultaneously pull 125 the ingot from the mold with an effort equal to said pressure.

2. In an ingot stripper, means for exerting downward pressure on a mold, means for pulling an ingot away from the mold, and 130

means for placing the pulling strain upon the first mentioned means.

3. In an ingot stripper, means adapted to rest upon a mold, tongs to engage an ingot carried by the mold, operating mechanism for the tongs, and means for placing strains from the operating mechanism upon the first mentioned means.

4. In an ingot stripper, means for holding a mold down, tongs for pulling an ingot from the mold, means including a screw having positively pitched threads for operating said tongs, and means for transferring strains placed on the screw to the first mentioned means.

5. In an ingot stripper, a housing, arms pivotally mounted on the housing and adapted to rest on an ingot mold, means for pulling an ingot from the mold, and means for transferring strains from the last mentioned means on to said housing, whereby the latter, through the arms, places the burden on the mold.

6. In an ingot stripper, a housing, arms pivotally connected to said housing and adapted to engage an ingot mold, means for moving the free ends of the arms toward or away from each other, means operatively connected to the housing for pulling an ingot from the mold, and means for transferring strains from the last mentioned means on to said housing, whereby the arms place such burden on the mold.

7. In an ingot stripper, a housing, mold engaging arms pivotally connected to said housing, extensions on said arms, and means for moving said extensions toward or away from each other.

8. In an ingot stripper, a housing, mold engaging arms pivotally connected to the housing and having extensions, double ended rocking levers operatively connected to said extensions, and supporting cables connected to the opposite ends of said double ended levers, whereby when the weight of the housing and arms is placed on certain of said cables, the arms will be opened, and when placed on the other cables, the arms will be closed.

9. In an ingot stripper, tong levers, fulcrum means for the levers arranged intermediate the ends of the latter, a member movable toward and away from said fulcrum means, diverging slots provided on the member, trunnions on the levers engaging said slots, and a ram for reciprocating said member.

10. In an ingot stripper, in combination with ingot gripping tongs, a cap for manipulating said tongs, a ram connected to the cap, a nut connected to the ram, and a screw adapted to manipulate the nut for moving the cap toward or away from said levers.

11. In an ingot stripper, ingot gripping levers, a member for manipulating said levers, a double screw operatively connected to

said cap, a nut engaging the screw, and means for imparting strains from the nut on to the mold in which the ingot is located.

12. In an ingot stripper, a housing, a double screw in the housing, ingot gripping tongs, an operating member for the tongs operatively connected to said screw, mold engaging arms mounted on the housing, and means for imparting strains from the screw on to said housing and arms. 75

13. In an ingot stripper, a housing, means for raising and lowering said housing, a double screw rotatably and axially movable in the housing, means for rotating said screw, mold engaging arms operatively connected to said housing, a stationary nut in the housing engaging said screw, a second nut engaging another portion of the screw, tongs supported by said housing, and means actuated by the second nut for opening and closing said tongs. 80 85

14. An ingot stripper as claimed in claim 13, in which the tongs are supported by rods that slidably engage the housing, and buffer springs for the rods, supported by said housing. 90

In testimony whereof, we have signed this specification.

CLINTON L. BIGLER.
JOHN KLOOS.
